UNITED STATES PATENT OFFICE.

GEORGE F. PAWLING, OF PHILADELPHIA, PENNSYLVANIA.

SCREED SUPPORT.

Application filed August 9, 1924. Serial No. 731,055.

This invention, stated in its broadest terms, relates to concrete construction and has more especial relation to means for supporting a screed with respect to metal lath 5 and in interlocked relation therewith.

As at present practiced a wood-blocking-piece is wired to place upon metal lath and the screed or nailing piece is nailed to the wood-blocking-piece. From an engineering 10 view-point this is an unsatisfactory method of procedure for the following reasons:—

(1) The distance from the lath to the top of the nailing piece is not always the same.

15 (2) There is nothing present with which to interlock the support with respect to the lath.

(3) Due to the fact that the blocking-point is necessarily thin it very frequently 20 splits when the nailing piece is nailed to it, making it necessary to re-wire a new blocking-piece, thus rendering the whole operation unnecessarily expensive.

(4) A wood-blocking-piece is not a satisfactory support since it displaces concrete which is required for the strength of the 25 floor structure.

The leading object of the present invention is to overcome the above described 30 disadvantageous features and provide a structure of the character under discussion in which my novel screed supports are first positioned upon and interlocked directly with metal lath and in proper alignment, 35 after which concrete is poured upon the lath and around the positioned supports. By such construction not only am I enabled to use lighter and cheaper grade of metal thus reducing production and shipping charges 40 but the cost of positioning the supports upon the job is reduced, because of the ease and rapidity with which the same may be caused to engage with the slotted parts of metal lath. A further object resides in the 45 provision of a novel form of screed support whereby the results outlined in the leading object may be obtained.

A further object of the present invention resides in the providing of general details 50 of construction and arrangement of parts as will hereinafter more fully appear.

The invention consists of the novel construction hereinafter described and finally 55 claimed.

The nature, characteristic features and scope of the invention will be more fully

understood from the following description taken in connection with the accompanying drawings forming part hereof, and in which:—

Fig. 1 is a fragmentary view in plan of metal lath having my novel screed supports positioned thereupon.

Fig. 2 is a view in section, drawn to an enlarged scale, and illustrating concrete as 65 being poured around a screed support, and

Fig. 3 is a perspective view of one of my novel screed supports.

For the purpose of illustrating my invention, I have shown in the accompanying 70 drawings one form thereof which is at present preferred by me, since the same has been found in practice to give satisfactory and reliable results, although it is to be understood that the various instrumentalities 75 of which my invention consists can be variously arranged and organized and that my invention is not limited to the precise arrangement and organization of the instrumentalities as herein shown and described. 80

The screed support of the present invention is best seen in Fig. 3. In practice it is made of relatively thin and inexpensive sheet metal, stamped out in one piece and bent to form metal lath engaging tongues and a U-shaped, 85 screed seat. The screed support, specifically stated, comprises spaced, parallel, flat members 1, perforated as at 2 for nail reception. Substantially midway of the extent of said members is a cross-piece 3, which together 90 with the perforated extremities of members 1, forms a U-shaped screed seat. The opposite ends of members 1 and the ends of seat 3 are extended in parallel, abutting relation as at 4—5 to provide a double thickness of material. These combined parts are each bent inwardly to form lath penetrating 95 tongues 6, to also provide a double thickness of material. The tongues may be slightly tapered, as clearly shown in Fig. 1, for ready 100 insertion through the slotted parts of a metal lath. Obviously the screed support may be made from several pieces of material, properly secured together, although I prefer the integral structure. For illustrative purposes 105 I have shown metal lath consisting of ribbed portions 7 between adjacent ribs of which are a plurality of slotted portions 8 bridged by webs 9, the slots and webs between alternate ribs 7 being arranged in staggered relation. However, my novel screed support may 110 be employed in connection with other forms

of slotted metal lath. In use with metal lath properly supported upon beams, not shown, an unskilled workman may quickly and readily interlock screed supports with respect to the lath by insertion of the tongues 6 through the slots 8 and beneath the webs 9, a screed support, thus attached, spanning three sets of webs 9, as clearly shown in Fig. 2. Because the various slotted parts of the metal lath are evenly divided, the various screed supports may be readily aligned and they retain their original position which is most desirable when securing screed 10 to place. The screed 10 is accommodated within the U-shaped parts of the supports and is secured thereto by means of nails.

With the above described parts in place concrete is poured therearound as plainly seen in Fig. 2, and when set, the screeds are fixed to the supports; the supports are fixed to the metal lath; and all the parts are relatively fixed by the concrete.

It will now be apparent that I have devised a novel and useful construction which embodies the features of advantage enumerated as desirable in the statement of the invention and the above description and while I have in the present instance shown and described the preferred embodiment thereof which has been found in practice to give satisfactory and reliable results, it is to be understood that the same is susceptible of modification in various particulars without departing from the spirit or scope of the invention or sacrificing any of its advantages.

What I claim is:—

1. In a construction of the character stated suitably supported metal lath, a screed-support supported wholly by said lath which screed-support includes side members and a

cross-piece to accommodate a screed, said side members each terminating in a tongue for interlocking connection with said metal lath, a screed supported upon said cross-piece and means for attaching said screed to said side pieces.

2. In a construction of the character stated suitably supported metal lath, a screed-support supported wholly by said lath which screed-support includes side-members and a cross-piece to accommodate a screed, said side members each terminating in a horizontally disposed tongue for interlocking connection with said metal lath, a screed supported upon said cross-piece and means for attaching said screed to said side pieces.

3. In a construction of the character stated suitably supported metal lath, a screed-support supported wholly by said lath which screed-support includes side members and a cross-piece to accommodate a screed, said side members each terminating in a horizontally disposed inwardly extended tongue for interlocking connection with said metal lath, a screed supported upon said cross-piece and means for attaching said screed to said side pieces.

4. In a construction of the character stated suitably supported metal lath, a screed-support supported wholly by said lath which screed-support includes side members arranged in abutting, parallel position and having plane surfaces and a cross-piece to accommodate a screed, said side members each terminating in a tongue for interlocking connection with said metal lath, a screed supported upon said cross-piece and means for attaching said screed to said side pieces.

In testimony whereof, I have hereunto signed my name.

GEO. F. PAWLING.
